UNITED STATES PATENT OFFICE

WILLIAM S. ELLIOT, OF NORTHAMPTON, MASSACHUSETTS, ASSIGNOR, BY MESNE ASSIGNMENTS, TO PRO-PHY-LAC-TIC BRUSH COMPANY, OF WILMINGTON, DELAWARE, A CORPORATION OF DELAWARE

BRUSH CLEANING MACHINE

Application filed August 10, 1929. Serial No. 384,852.

This invention relates to machines for cleaning brushes such, for example, as hair and clothes brushes.

The chief object of the invention is to provide a machine of the character described capable of cleaning brushes of various shapes and sizes. This is accomplished in part by providing a machine with which a number of different brush holders can be used, each holder being formed to accommodate brushes of different shapes and sizes, the several holders being detachable and interchangeable so that the machine may be employed to clean brushes of any specified shape or style, desired. To cause a thorough cleaning of the brushes, means is provided for maintaining the brushes to be cleaned in contact with the cleaning element during the movement of the holder through a predetermined space. Other objects of the invention will appear from the following description and appended claims, when taken in connection with the accompanying drawings, in which:

Fig. 1 is a top plan view of the machine of my invention.

Fig. 2 is a longitudinal section of the machine in Fig. 1.

Fig. 3 is an end elevation of the machine looking toward the left of Figs. 1 and 2, and

Fig. 4 is a section taken substantially on the line 4—4, Fig. 2.

Before explaining in detail the present invention, it is to be understood that the invention is not limited in its application to the details of construction and arrangement of parts illustrated in the accompanying drawings, since the invention is capable of other embodiments and of being practised or carried out in various ways. Also it is to be understood that the phraseology or terminology employed herein is for the purpose of description and not of limitation, and it is not intended to limit the invention beyond the terms of the several claims hereto.

appended as considered in view of the prior art and the requirements thereof.

The machine of my invention comprises a base and frame structure shown as a whole at 10. Adjacent one end of the machine, preferably at the left side thereof, as shown in Figs. 1 and 2, is an outboard hanger stand 11 which, together with the bearings 12, supports the horizontal drive shaft 13. The outer end of the shaft is mounted in a bearing sleeve 14. Mounted upon the shaft 13 between the outboard hanger stand and the frame 10 of the machine is a pair of pulleys 15 and 16 of equal diameter. The pulley 15 is an idler pulley loose on the shaft 13, whereas the pulley 16 is fixed to the shaft to rotate therewith. A third pulley 17 of smaller diameter is also fixed to the shaft and positioned next to the pulley 16. The base of the machine frame 10 supports, by means of a bearing 18, a second horizontal shaft 19, which carries on its outer end a fixed or tight pulley 20. A belt 21 connects the pulleys 17 and 20 and a drive belt 22 connected with a drive shaft (not shown) serves to transmit power from said drive shaft to the pulleys 15 and 16. A belt shifter (not shown) of any desired construction may be employed.

Supported within the frame work of the machine and fixed to the shaft 13 is a brush cleaning wheel or drum 23, the periphery of which is provided with radially projecting metal teeth or the like 24 similar to a card, said teeth preferably comprising pins or nails set in a length of canvas belting 23a wrapped about and secured to said periphery. The cleaning wheel or drum is positioned for rotation within a metal housing which may be in the form of a container 25. The container is so positioned that the ends of the teeth 24 project above the upper end thereof.

Carried by the frame work of the machine and at right angles to the shaft 13 are vertical bearings 26 and 27 which support a vertical shaft 28, having at its upper end a square

shank 28a and a threaded end 28b to receive a washer and nut 37. A thrust bearing 31 surrounds the shaft 28 adjacent its upper end. The lower end of the shaft 28 is connected through a coupling 32 with a worm gear 33 mounted in a housing 34 supported by the frame 10. The housing or casing has an extension 34a by which it is attached to the frame 10 in any suitable manner, such as by bolts 34b. The shaft 19 is connected by means of a coupling 35 with a shaft 19a journaled in the casing 34 and carrying upon its outer end a worm 36 meshing with the worm gear 33. The worm and worm gear constitute a reducer, the reduction being approximately at the ratio of 48 to 1. It will be seen, therefore, that the shaft 13 is driven much more rapidly than the shaft 28.

One of the travelling brush carriers or 20 holders is shown as a whole at 38. It comprises, preferably, a hub portion 38a having a square hole therethrough, the hub having a disk 38b to which a notched disk or plate 38c is secured in any suitable manner. The plate 38c is provided around its periphery with notches or sockets 39 which are shaped to conform to the shape of a brush back or handle, and so formed as to receive and loosely support the brush back. Brush holders 25 having disks 38c formed with pockets of any desired size and shape, dependent upon the style of brush to be supported, may be provided, said brush holders being detachable and interchangeable, and being held in place 30 upon the square shaft portion 28a by means of the nut and washer 37.

Mounted upon the frame of the machine is a presser block comprising an arm 41 hinged at 42 to the frame of the machine and having 40 a head 43. The head is provided with depending side flanges which receive and support journals on the ends of the rollers 44. It will be noted (Fig. 1) that the presser block overhangs the travelling brush holder 45 or carrier 38 at a point immediately above the cleaning drum 23, so that the rollers 44 engage the backs of the brushes 40. By providing rollers, the movement of the holder and brushes over the cleaning drum is not retarded. By hinging the arm 41, the presser head 43 is, in effect, resiliently supported above the brush backs and it will be understood that the weight of the head 43 is sufficient to apply pressure to the back of the brushes to be cleaned so as to hold their bristles in contact with the wire teeth 24 of the cleaning drum. By providing a construction such as described, it will be seen that the brushes to be cleaned are loosely supported in their respective sockets in the travelling brush holder, so that they can be easily inserted and mechanically removed by means of the ejector plate 45 secured by screws 46 50 to the frame of the machine. As they are

removed by the plate 45, the brushes fall into the container or receptacle 47.

In operation, the brush holder is rotated in a clockwise direction, as indicated by the arrow on Fig. 1, and the workman feeds the brushes to be cleaned to the sockets 39 at the point A. As the holder rotates, it moves the brushes into position over the teeth 24 of the cleaning drum, and the head 43 of the presser engages the top or back of the successive 75 brushes and maintains their bristles in contact with said teeth during the movement of the brushes over said drum. After the cleaned brush is carried around to the point B, the ejector plate 45 engages the brush 80 bristles and removes the brush from its socket 39, directing the cleaned brush into the receptacle 47.

From the foregoing it will be seen that I have provided a machine capable of cleaning brushes of various sizes and shapes by a substantially continuous operation, the only manual labor required being that of feeding the brushes to the sockets in the brush carrier as it rotates. The brush carriers are detachable, as above described, and are interchangeable and may be quickly detached and applied to the shaft 28.

I claim:

1. In a brush cleaning machine, in combination, a rotating cleaning drum, a travelling brush holder for moving the brushes to be cleaned across the periphery of said drum in a plane at right angles to the plane of rotation of the latter, and common driving means 100 for said drum and brush holder.

2. In a brush cleaning machine, in combination, a rotatable cleaning drum, a detachable plate having brush receiving sockets 105 therein rotatable in a plane at right angles to the plane of rotation of said drum for moving brushes to be cleaned across the periphery thereof, and common driving means for said drum and plate.

3. In a brush cleaning machine, in combination, a rotatable cleaning drum, a brush carrier for moving brushes to be cleaned successively into and out of engagement with said cleaning drum, means for driving said drum and carrier, and means positioned adjacent the carrier for maintaining the successive brushes carried thereby in contact with said drum.

4. In a brush cleaning machine, in combination, a rotating cleaning drum, a travelling brush holder for moving the brushes to be cleaned across the periphery of said drum in a plane at right angles to the plane of rotation of the latter, common driving means for said drum and brush holder, and a presser block positioned at one side of said drum and travelling brush holder for yieldingly engaging the backs of successive brushes to be cleaned to maintain the bristles thereof in contact with said drum.

5. In a brush cleaning machine, in combination, a frame, a rotating cleaning drum, a travelling brush holder for moving the brushes to be cleaned across the periphery of said drum in a plane at right angles to the plane of rotation of the latter, common driving means for said drum and brush holder, a presser block having an arm hinged to said frame positioned at one side of said travelling
10 brush holder and drum, and rollers carried by said block adapted to engage the backs of successive brushes to maintain the bristles thereof in contact with said drum.

In testimony whereof I affix my signature.
WILLIAM S. ELLIOT.
